C. E. SWICK,
DELIVERY MECHANISM.
APPLICATION FILED MAR. 16, 1918.

1,354,144.

Patented Sept. 28, 1920.

UNITED STATES PATENT OFFICE.

CLYDE E. SWICK, OF SAN FRANCISCO, CALIFORNIA, ASSIGNOR TO HAWLEY PULP AND PAPER COMPANY, A CORPORATION OF OREGON.

DELIVERY MECHANISM.

1,354,144.

Specification of Letters Patent.

Patented Sept. 28, 1920.

Original application filed October 8, 1915, Serial No. 54,828. Divided and this application filed March 16, 1918. Serial No. 222,857.

To all whom it may concern:

Be it known that I, CLYDE E. SWICK, of San Francisco, in the county of San Francisco and in the State of California, have 5 invented a certain new and useful Improvement in Delivery Mechanism, and do hereby declare that the following is a full, clear, and exact description thereof.

My invention has for an object to provide 10 a mechanism adapted to receive webs of paper after the same have been operated upon by a machine, and deliver the webs properly therefrom.

While my invention is not restricted in use 15 to any particular machine, it is especially adapted to be used in connection with the paper folding machine described and claimed in my copending application No. 54,828, filed October 8th, 1915, of which the 20 present application is a division.

For purposes of illustration I have shown 25 one embodiment of my invention which, however, is to be considered merely as illustrative of many other embodiments within the principle thereof. In the drawings:—

Figure 1 is a side elevation of a portion of the machine embodying my invention; and

Fig. 2 is a central section of such a machine, the section being taken parallel to the plane of Fig. 1.

I have illustrated my invention as used 30 in connection with the paper interfolding machine described in my copending application, Serial No. 54,828 filed October 8th, 1915, but only such parts of the said machine 35 which are necessary to a disclosure of the principle of my invention, are shown, reference being hereby made to the said application for a full disclosure of the complete 40 machine. Such machine comprises, in a general way, a frame 1 within which are placed two similar paper interfolding rolls 2 and 3, mounted respectively upon shafts 4 and 5, 45 which shafts are driven by suitable gears 6 and 7.

As the two cylinders, together with the delivery mechanism associated with each, are 50 exactly alike, with the exception of being displaced angularly 90° with respect to one another, but one of such cylinders and delivery mechanism, are herein described. The interfolding cylinder 2 has thereon a 55 pair of stationary paper gripping jaws 8, adapted to coöperate with movable jaws 9,

which latter are actuated by arms 10 having rollers 11 engaging the cam surface 12. Blades 13 are mounted respectively at angles of 90° from the gripping jaws 8 and 9, so that, as the cylinders 2 and 3 rotate, the 60 blades 13 of one cylinder will pass in between the gripping jaws 8 and 9 of the other with result that webs of paper, passing over the rolls 2 and 3, are alternately folded within and gripped by such jaws. As the 65 jaws 8 and 9 pass out of engagement with the blades 13 after having received the paper therein, rollers 11 are moved by cam surface 12 to open the jaws so as to disengage them from the folded webs of paper. Suitable 70 devices, not necessary to be described or shown in connection with the present invention, ordinarily are also used to sever the webs of paper at proper points so as to produce folded or interfolded sheets of paper, 75 alternate sheets of which are gripped between the jaws 8 and 9 of roll 2 and roll 3.

In order to deliver the webs of paper from the roll 2, I employ a stripping arm 14 which is adapted to engage beneath the paper, and thus separate the latter from the roll; in the present form, such arm works in a groove 15 in the periphery of the roll 2, and is periodically moved into and out of operative position at proper intervals by 80 means of cams 16, which engage a roller 17 mounted upon the end of an arm 18 pivoted on a shaft 19, which arm 18 also carries the stripping arm 14.

A suitable coil spring 20 holds the roller 90 17 normally advanced, so that the stripping arm 14 is in withdrawn position.

Beneath the stripping arm 14 I have shown a fixed tumbler 21 which carries a rotatable shaft 22 having a tumbler arm 23 95 mounted thereon. A shaft 24 carries a gear 25 which engages with the gear 6 of roll 2, and an additional gear 26 on said shaft engages a gear 27 on shaft 22, so as to rotate the latter, together with the tumbler arm 23. 100

In the operation of the present embodiment of my invention, webs of folded paper will be gripped between the jaws 8 and 9, as above described, and stripping arm 14 will be raised by the engagement of cams 16 105 with roller 17, to extend into groove 15 between the webs of paper and the cylinder, as the said webs pass from the point of engagement between rolls 2 and 3. Movable jaws 9 are then opened by the engagement 110

of roller 11 with cam surface 12, and the released webs of paper pass between stripping arm 14 and the stationary tumbler 21. The folded webs of paper are held between 5 these two members until the tumbler arm 23 is rotated to remove the paper from between the same, and deliver it to a traveling belt 28 for instance.

It will be understood that a similar 10 delivery mechanism operates upon the roll 3 to deliver the folded webs of paper from the same alternately with the webs which are delivered from roll 2, if the delivery mechanism be used in connection with the illustrated type of folding machine.

While I have shown a specific embodiment of my invention, it is obvious that many changes will be made therein which will still be within the spirit thereof as defined 20 in the appended claims.

I claim:

1. In combination, a paper folding roll having a groove therein, a stripping arm mounted adjacent thereto, and an operating 25 means driven from the roll for periodically moving said arm into position within the groove to engage the folded paper.

2. In combination, a paper folding roll having a groove therein, a pivoted stripping 30 arm mounted adjacent thereto, and a cam mounted on said roll for periodically moving said arm into position within the groove to engage the folded paper.

3. In combination, a paper folding roll, 35 an arm mounted adjacent thereto and adapted to strip the paper from the roll, means for temporarily holding the paper when so stripped comprising one fixed member, and means for removing the paper from said holding means.

4. In combination, a paper folding roll, a stripping arm mounted adjacent thereto, means for periodically moving said arm into and out of position between the folded paper 45 and the roll, and a member adapted to be engaged by said arm to hold the paper between the two.

5. In combination, a paper folding roll, a stripping arm pivoted adjacent thereto, 50 means for periodically moving said arm into and out of position between the folded paper and the roll, and a fixed tumbler adapted to be engaged by said arm when in inoperative position to hold the paper 105 against said fixed tumbler.

6. In combination, a paper folding roll, a stripping arm mounted adjacent thereto, means for periodically moving said arm into and out of position between the folded paper

and the roll, a member adapted to be engaged by said arm to hold the paper between the two, and means for removing the paper from between said member and arm.

7. In combination, a paper folding roll, a stripping arm pivoted adjacent thereto, 65 means for periodically moving said arm into and out of position between the folded paper and the roll, a fixed tumbler adapted to be engaged by said arm when in inoperative position to hold the paper against said 70 fixed tumbler, and a rotating tumbler arm adapted to remove the paper from between said stripping arm and fixed tumbler.

8. In combination with a paper roll, of 75 a stripping device for the same comprising a pair of members one of which is fixed adapted to receive the paper therebetween, and means for removing the paper from between said members.

9. The combination of a paper roll, of a 80 stripping device for the same comprising a stationary tumbler, a movable member adapted to direct the paper from the roll and to hold it in engagement with the stationary tumbler, and means adapted to remove the paper from engagement therewith.

10. In combination, a paper folding roll, a stripper for stripping the folded paper therefrom, and a stationary tumbler coöperating with the stripper to hold the folded 90 web of paper therebetween.

11. In combination, a paper folding roll, a stripper for stripping the folded paper therefrom, a stationary tumbler coöperating with the stripper to hold the folded web 95 of paper therebetween, and a tumbler arm for removing the folded web from the stripper and stationary tumbler.

12. In combination, a paper folding roll, an arm mounted adjacent thereto and adapted to strip the paper from the roll, means for temporarily holding the paper when so stripped, and means for removing the paper from said holding means comprising a fixed 105 tumbler.

13. In combination, a paper folding roll, means adapted to strip the paper from the roll, means for temporarily holding the paper when so stripped, and means for removing the paper from said holding means comprising a fixed tumbler.

In testimony that I claim the foregoing I have hereunto set my hand.

CLYDE E. SWICK.
